BUCKLE

Mike I. Garber and Hilary Goldberg, Johannesburg, Transvaal, Republic of South Africa, assignors to Miniwheel Limited, London, England
Filed May 31, 1962, Ser. No. 198,996
Claims priority, application Republic of South Africa, July 18, 1961, R 61/718
2 Claims. (Cl. 24—34)

This invention relates to buckles of the kind comprising a hinged, and preferably pronged, jaw which receives and clamps a strap (or a web) between itself and the base plate of the buckle to vary the effective length of the strap. It thus divides the strap into two zones, one of which is the zone in which the strap is, in use, under tension and the other of which is the untensed tail end of the strap.

These buckles are used on the straps which secure carriers to the outside of motor vehicles. The carriers may be mounted on the roof, when the straps may terminate in hooks which engage the guttering to each side of the body; or on the boot where the edges of the boot cover may be used to anchor the carrier.

One object of the invention is to provide a buckle which can be used for all these purposes.

According to the invention, the buckle comprises a base plate that is formed with two hooked ends, the hooks being of different types to engage two different categories of anchor. Thus, for instance, a strap may have to engage alternatively with the guttering of a motor car body, or with the rim of its boot.

Further according to the invention, the pivoted clamping jaw is straddled by two lateral slots, and the jaw is reversible. To this end, the clamping jaw may be hinged on lugs projecting upwardly from a rectangular plate, the edges of which are slidably received in lateral grooves on the base plate.

Two embodiments are illustrated in the accompanying drawings in which:

FIGURE 1 is a face view of the first embodiment;
FIGURE 2 is a side view;
FIGURE 3 is a side view of the second embodiment;
FIGURE 4 is a face view of the second embodiment;
FIGURE 5 is a fragmentary view showing one hook in use; and

FIGURE 6 is a fragmentary view showing the second hook in use.

In both embodiments, the base plate 10, which is bent from sheet metal, is formed at its ends with hooked portions 12, 14 of different shapes. The hook 12 is intended to engage the guttering on either side of a vehicle body, as shown in FIGURE 5. The hook 14 is intended to engage the edge of the boot of a vehicle, as shown in FIGURE 6. In the former case, means is included to clamp the hooked buckle in position. In FIGURES 1 and 2 the means is a loose bracket 18 which is moved into the cavity of the guttering and clamped by a wing nut 22 on a bolt 24. In FIGURE 3, the means are two screws 26 that are screwed through holes in a ledge 28 in the base plate 10, for their ends to bear against the flange 20.

The buckle proper consists, in both cases, of a pronged

2

jaw 30 pivoted on lugs 32 provided by bending upwardly the terminal zones of a sheet metal strip 33 to define between the pronged jaw and the strip a channel for a webbed strap 34.

5 The strap is passed through the channel with the jaw 30 pivoted to clear the channel and to lie parallel with the strap. The strap is drawn taut and released, whereupon the prongs are engaged by the strap to rotate the jaw about its pivotal axis and for the prongs to penetrate the strap 10 to anchor it.

As the buckle is reversible, it is necessary that the jaw 30 be also reversible. To this end, the strip 33 extends to each side of the lugs 32 to constitute tongues 36 that engage slidably in two parallel grooves 38, formed by 15 pressing out two slots 40, one to each side of the buckle and bending over the metal of the slots towards one another. The buckle is reversed by sliding strip 33 out of the slots 40, reversing it and sliding it back into place.

One utility of the buckle is that the change of direction 20 in the strap 34 as it leaves the pronged jaw 30 and passes through a slot 40 subjects the strap to substantial frictional constraint against slip and thus supplements and buttresses the jaw 30. Tension on the tail end of the strap causes the clamp to open and the frictional resistance to 25 movement of the strap through the slot is low enough for the strap easily to be drawn tight.

Finally, the base plate may be apertured to either side of the slots 40 as shown at 42 and possibly also in the hook formations as shown at 44 to receive anchoring bolts, 30 for instance those which hold a roof carrier in place. In this case the free end of the bolt is passed through the aperture and a nut anchors the base plate in position.

We claim:

1. A buckle comprising a base plate that is formed with 35 two hooked ends, the hooks being of different type to engage two different categories of anchor, two spaced slots parallel to the ends of the base plate, the slots being formed by pressing out adjacent tongues from the base plate and the tongues being bent over to define opposed grooves 40 between themselves, a rectangular plate with lugs projecting upwardly therefrom, and a clamping jaw hinged on the lugs, the rectangular plate being slidably and reversibly received in the grooves.

2. The buckle claimed in claim 1 in which one hook is 45 a plain hook for engaging over relatively thin edges and the other hook is provided with screw means for clamping an edge between the screw means and a part of the base plate.
